UNITED STATES PATENT OFFICE.

PORTER W. MUNSON, OF ST. LOUIS, MISSOURI.

DESIGN FOR A ROLLER TOY.

54,760.

Specification for Design. Patented Mar. 23, 1920.

Application filed May 8, 1919. Serial No. 295,787. Term of patent 7 years.

To all whom it may concern:

Be it known that I, PORTER W. MUNSON, a citizen of the United States, and resident of St. Louis, State of Missouri, have invented a new, original, and ornamental Design for a Roller Toy, of which the following is a specification.

Reference being had to the accompanying drawing forming part thereof,

Figure 1, is a perspective view of a roller toy showing the same from the front, and Fig. 2, is a perspective view thereof showing the toy from the rear.

I claim:

The ornamental design for a roller toy as shown.

PORTER W. MUNSON.
